(57) **CLAIM**

The ornamental design for a straw, as shown and described.

DESCRIPTION

FIG. 1 is a top perspective view of a straw.

FIG. 2 is a bottom perspective view of the straw of FIG. 1.

FIG. 3 is a rear elevation view of the straw of FIG. 1.

FIG. 4 is a right side elevation view of the straw of FIG. 1.

FIG. 5 is front elevation view of the straw of FIG. 1.

FIG. 6 is a left side elevation view of the straw of FIG. 1.

FIG. 7 is a top plan view of the straw of FIG. 1; and,

FIG. 8 is a bottom plan view of the straw of FIG. 1.

The evenly spaced broken lines and the areas within them in the drawings illustrate portions of the straw that form no part of the claimed design.

1 Claim, 3 Drawing Sheets
